UNITED STATES PATENT OFFICE.

FRANK WESTCOTT, OF SENECA FALLS, NEW YORK.

DESIGN FOR A RIGHT-LINE MEASURING-RULE.

SPECIFICATION forming part of Design No. 15,251, dated August 12, 1884.

Application filed June 5, 1884. Term of patent 7 years.

To all whom it may concern:

Be it known that I, FRANK WESTCOTT, a citizen of the United States, residing at Seneca Falls, in the county of Seneca and State of New York, have invented certain new and useful Improvements in Designs for Right-Line Measuring-Rules; and I do declare the following to be a full, clear, and exact description of the invention, such as will enable others skilled in the art to which it appertains to make and use the same, reference being had to the accompanying drawings, and to letters or figures of reference marked thereon, which form a part of this specification.

Figure 1 of the drawings is a representation of this design, and shows the obverse side of the ruler. Fig. 2 is a view of the reverse side. Fig. 3 is a perspective view.

This design has relation to right-line measuring rules.

In the accompanying drawings, illustrating this design, the letter A designates the ob-

verse or face of the rule, and B the reverse or back thereof. The rule is graduated along its 25 marginal portion, as indicated at C, and in the portion adjacent, which extends longitudinally, are printed in series small pictures, D, of animals, as shown. These small pictures represent, in some instances, entire animals, and 30 in others only the heads thereof. A series of small pictures, E, may likewise be printed on the back of the rule.

What I claim, and desire to secure, is -

The design of a right-line rule, having the 35 marginal graduation C, and in the longitudinal portion adjacent thereto a series of printed pictures of animals, as shown and described.

In testimony whereof I affix my signature in presence of two witnesses,

FRANK WESTCOTT.
